SELF-CLEANING PELLET FEEDER

Jack A. Smith, 3005 Zinnia Court,
Golden, Colo. 80401

Filed June 22, 1967, Ser. No. 7,565

Term of patent 14 years

(Cl. D30—15)

FIG. 1

FIG. 2

FIG. 3

FIG. 4

FIG. 5

FIG. 6

FIG. 7

FIG. 8

FIG. 1 is a bottom perspective view of a self-cleaning pellet feeder, showing my new design.

FIG. 2 is a rear elevational view thereof.

FIG. 3 is a bottom plan view thereof.

FIG. 4 is a side elevational view thereof, showing the door in partially opened condition.

FIG. 5 is a side elevational view of another embodiment of the design, the undisclosed portions of the embodiment being substantially the same as in the FIG. 1 embodiment.

FIG. 6 is a top plan view of FIG. 1.

FIG. 7 is a fragmentary top plan view of still another embodiment of the design, the undisclosed portions thereof being substantially the same as in the FIG. 1 embodiment.

FIG. 8 is a front elevational view of the FIG. 1 embodiment.

The undisclosed sides of the design embodiments of FIGS. 2 and 3 are mirror images respectively of the sides shown.

I claim:

The ornamental design for a self-cleaning pellet feeder, substantially as shown and described.
